UNITED STATES PATENT OFFICE.

WILLIAM BRYAN MORROW, OF SHIPPENSBURG, PENNSYLVANIA.

SCREEN-DOOR FASTENER.

1,155,953.

Specification of Letters Patent.

Patented Oct. 5, 1915.

Application filed April 16, 1915. Serial No. 21,901.

To all whom it may concern:

Be it known that I, WILLIAM BRYAN MORROW, a citizen of the United States, residing at Shippensburg, in the county of 5 Cumberland and State of Pennsylvania, have invented new and useful Improvements in Screen-Door Fasteners, of which the following is a specification.

This invention relates to improvements in 10 door latches especially applicable to light door frames such as screen doors and the like.

The invention contemplates the provision 15 of a latch which when operatively associated with the door, the latter cannot be opened from the outside, and including a single element for interchangeable engagement with the latch lever at remote points whereby said latch may be locked in operative or in- 20 operative position as desired.

Among other features the invention embodies simplicity in construction, and efficiency in operation, the invention residing in the construction, combination and ar- 25 rangement of parts hereinafter more fully described.

In the drawing forming part of this applica- 30 tion like numerals of reference indicate similar parts in the several views and in

Figure 1 is a transverse section through the door showing the latch in operative position, the door jamb being in elevation. Fig. 2 is a similar view showing the latch 35 in inoperative position. Fig. 3 is a sectional view taken on line *a*—*a* of Fig. 1. Fig. 4 is a detail view of the latch lever.

In the specific embodiment of the invention illustrated, the same consists of a pair 40 of spaced members 5 and 6 respectively, fixed to the door jamb A, the inner edge of the member 6 being cut away as at 7 for the reception of the semicircular bulged portion 8 of the lever 9 to permit the rock- 45 ing movement of the latter which is pivoted between the members 5 and 6 as shown. The lever at the opposite sides of the bulged portion 8 is adapted to engage the upper edge of the member 6 to limit its movement 50 in opposite directions. A plate 10 covers the members 5 and 6 and is secured thereto in any suitable manner. The forward end of the lever is adapted to enter an elongated recess 11 in the door B, a keeper plate 55 12 extends transversely across the recess at the lower end thereof and is terminally se-

cured to the door in any suitable manner. The forward end of the lever is formed with a depending hook 13 adapted to hook over the upper edge of the plate 12 when positioned within said recess. The under side of the hook is beveled as at 14 so as to ride upon the upper edge of the plate 12, on closing of the door, and subsequently gravitate into operative association therewith. 60 With the lever thus positioned within the recess 11, the dog 15 freely pivoted to the jamb A above said lever is swung forwardly into engagement with the projection 16 ex- 65 tends upwardly from the upper edge of the lever and fitted within a transverse groove 17 in the end of the dog, whereby the lever is effectively held in operative position, and the door securely locked in a manner to prevent of its being opened from 70 the outside.

As clearly shown in Fig. 2 the dog 15 is capable of being reversed, or in other words swung rearwardly into engagement with the projection 18 rising from the op- 75 posite end of the lever to maintain the latter in inoperative position to permit the door to be opened and closed when desired. The projection 18 has a beveled surface 19 for engagement with a similar surface 20 on the lever 15, so that when the latter is swung 80 rearwardly into engagement with the end of said lever, the latter will be depressed thus lifting the forward end of the lever 85 out of engagement with the keeper plate 12 and locked in inoperative position, the bevelled surfaces 18 and 19 obviating any binding action between their respective parts 90 during this operation. The member 5 serves as a stop for the pivot dog 15 limiting its 95 movement in either direction, and supports the same in operative engagement with the lever.

It is believed that from the foregoing de- 100 scription the nature and advantages of the invention will be readily apparent without requiring a more extended explanation and therefore the same has been omitted. It is to be understood however, that various changes may be resorted to when desired 105 as fall within the scope of the appended claim.

What is claimed is:—

A door latch and lock therefor comprising in combination, a straight lever pivoted 110 at a point between its ends to the jamb of the door for rocking movement, said lever

2
being adapted to enter a recess in said door arranged at a right angle to said lever, a keeper plate secured to the door and extending across the lower end of the recess, 5 said lever having a hooked end adapted to gravitate into engagement with said plate upon entering said recess, projections rising from the upper surface of the lever at spaced points, a pawl freely pivoted above 10 said lever and having a notched end portion for interchangeable engagement with

said projection whereby to maintain said lever in either operative or inoperative position, and means for limiting the rocking movement of said lever.

15

In testimony whereof I affix my signature in presence of two witnesses.

WILLIAM BRYAN MORROW.
